UNITED STATES PATENT OFFICE.

HARRY M. KORETZKY, OF NEW YORK, N. Y.

FLASH LIGHT.

Application filed June 27, 1921. Serial No. 480,597.

To all whom it may concern:

Be it known that I, HARRY M. KORETZKY, a citizen of the United States, and resident of the city of New York, borough of Manhattan, county of New York, and State of New York, have invented a new and Improved Flash Light, of which the following is a full, clear, and exact description.

My invention relates to a flashlight and 10 aims to provide certain new and useful improvements in connection with a device of this character.

In connection with flashlights it is a well appreciated fact that considerable difficulty 15 has been experienced incident to the fact that if the flashlight were laid upon or adjacent to a metallic object that irrespective of the fact that the switch of the flashlight was open, a circuit would be completed and 20 the battery would thus become exhausted.

A further difficulty which has been experienced is that the end or contact portion of the bulb associated with the flashlight has often been injured due to the central electrode 25 of the uppermost cell within the flashlight, striking against this portion of the bulb.

Still another objection to present flashlights is that the cost of producing the same 30 is relatively high incident to the fact that a number of details of construction have heretofore been regarded as essential, which details have constituted the major portion of the cost of manufacture.

With these objections in mind my present 35 invention aims to provide a flashlight the primary object of which is a construction by means of which an operator may manipulate the parts to absolutely preclude any danger 40 of a circuit becoming accidentally closed, resulting in the exhausting of the battery, so that the operator may pack the flashlight among metallic objects without feeling any fear upon this point.

A further object of my invention is the 45 provision of a flashlight which shall include means virtually precluding any danger of the stem of the bulb becoming injured incident to contacting with any portion of the 50 uppermost cell within the flashlight.

Another object of this invention is that of 55 constructing a flashlight including the advantages set forth in the preceding paragraphs which shall also be constructed in such a manner as to permit of its being man-

ufactured for a far smaller amount that has been considered heretofore possible.

Still further objects of this invention will appear in the annexed specification taken in connection with the drawings which latter present one practical embodiment of the same.

In the drawing is a sectional side view taken through a flashlight embodying my improved construction.

Referring now more particularly to the drawing it will be seen that the reference numeral 5 indicates the casing of the flashlight which in this instance is of any desirable insulating material, and has any suitable type 70 of switch 6 mounted upon its upper face, said switch being capable of bridging the gap existing between the strips 7 and 8 within the casing 5 and extending in the conventional manner to points adjacent the ends 75 of the same.

Also in the conventional manner, the casing 5 has a reflector 9 associated with one of its ends, which reflector mounts a bulb 10, electrical energy for the latter being furnished by means of cells 12 positioned within the casing 5 and retained thereby by means of a cap 11.

Contrary to the conventional construction however, it will be noted that the cap 85 11 in the embodiment illustrated is not provided with a spring commonly utilized for causing an intimate contact between the terminals of the cells, but that the cap 11 has its center dished or otherwise extending inwardly as at 13 to press into intimate engagement with the butt end of the innermost cell 12. Further a spring 14 is interposed between the inner face of the reflector 9 to which it is preferably secured, and the upper 95 face of the outermost cell 12.

Spring 14 serves to normally separate the central electrode 15 of the outermost cell 12, from the stem of the bulb 10, so that even if the switch 6 should be closed or a metal object should be brought to extend between the cap 11 and clamping ring 16 of the reflector no circuit will be completed, thus avoiding a wastage of current. However if the operator desires to close the circuit this 100 105 may be accomplished by simply rotating the cap 11 to an extent sufficient to cause the outer end of the electrode 15 to press against the stem of the bulb 10 whereupon an operation of the switch 6 will cause an actuation 110

2
of the bulb 10. Upon the operator being through with the flashlight the same may be laid aside without any fear of the battery becoming accidentally exhausted, in that the operator may rotate the cap 11 along the screw threads 17 provided for this purpose and the spring 14 will then be free to press the electrode 15 of the outermost cell 12 clear of the stem of the bulb 10 so that an accidental completing of the circuit will be precluded.

Obviously numerous modifications of structure might readily be resorted to without in the least departing from the spirit of 15 my invention, which I claim as;

In a flashlight of the type including a combined battery case, light holder and handle, and of the type including a bulb in said holder and constituting said light at one 20 end of the handle and a removable cap at the other end of the handle, and further of the type including a battery slidable in the handle between bulb and cap and an expan-

sile coil spring in said handle immediately adjoining the battery, the combination of 25 shock absorbing means between battery and bulb, said means comprising the interposition of such spring between bulb and battery, and means for precluding accidental lighting of the bulb by the battery, the 30 means last mentioned including said spring and a circuit having therein bulb and battery and also having therein a plurality of make and break points one of which points is normally held open at an electrode of the 35 battery by said spring, and a manually actuatable switching device at the exterior of the handle and normally holding open the other of said points, there being provided 40 coacting threads on said handle and cap for manual relative adjustment of handle and cap, all whereby said cap must be screwed up on the handle and also such switching device must be manually actuated in order 45 to put the bulb in circuit with the battery.

HARRY M. KORETZKY.
